US0D1023276S

(12) **United States Design Patent** (10) Patent No.: **US D1,023,276 S**
(45) Date of Patent: ** Apr. 16, 2024

(54) **PRE-FILTER**

(71) Applicant: **HUSQVARNA AB**, Huskvarna (SE)

(72) Inventors: **Karl Elmestrånd**, Sävedalen (SE);
Axel Sjöberg, Västra Frölunda (SE)

(73) Assignee: **HUSQVARNA AB**, Huskvarna (SE)

(**) Term: **15 Years**

(21) Appl. No.: **29/816,416**

(22) Filed: **Nov. 22, 2021**

(30) **Foreign Application Priority Data**

May 26, 2021 (EM) 008553895-0001

(51) LOC (14) Cl. **23-04**

(52) U.S. Cl.

(57) **CLAIM**

The ornamental design for the pre-filter, as shown and described.

DESCRIPTION

FIG. 1 is a perspective view of a pre-filter of the present invention;

FIG. 2 is a front view of the pre-filter of FIG. 1;

FIG. 3 is a rear view of the pre-filter of FIG. 1;

FIG. 4 is a left side view of the pre-filter of FIG. 1;

FIG. 5 is a right side view of the pre-filter of FIG. 1;

FIG. 6 is a top view of the pre-filter of FIG. 1; and,

FIG. 7 is a bottom view of the pre-filter of FIG. 1.

The broken lines of FIGS. 1-7 depict portions of the pre-filter that form no part of the claimed design.

1 Claim, 7 Drawing Sheets
